UNITED STATES PATENT OFFICE.

JOHN O. HEINZE, OF SPRINGFIELD, OHIO, ASSIGNOR TO THE JOHN O. HEINZE COMPANY,
OF SPRINGFIELD, OHIO, A CORPORATION OF OHIO.

STARTING DEVICE FOR INTERNAL-COMBUSTION ENGINES.

1,262,666.

Specification of Letters Patent. Patented Apr. 16, 1918.

Application filed March 1, 1916. Serial No. 81,397.

To all whom it may concern:

Be it known that I, JOHN O. HEINZE, a citizen of the United States, residing at Springfield, in the county of Clark and 5 State of Ohio, have invented certain new and useful Improvements in Starting Devices for Internal-Combustion Engines, of which the following is a specification.

This invention relates to improvements in 10 starting devices for internal combustion engines, and it more particularly relates to the means for connecting and disconnecting the starting motor with the crank shaft of the engine.

15 The object of the invention is to simplify the construction and make more effective the operation of devices of this character.

In the accompanying drawings:—

Figure 1 is an end view of a portion of an 20 internal combustion engine, such for instance as the fly wheel thereof and the starting motor thereof showing my improvements applied thereto.

Fig. 2 is a section on the line 2—2 of 25 Fig. 1.

The improvements are particularly intended for the starting system of a motor vehicle and in the drawings, 1 represents a crank shaft of an internal combustion engine 30 and 2 the fly wheel thereof having thereon gear teeth 3 to which the power for starting the engine is applied from an electric motor 4 in the following manner: The shaft 5 of the motor has fixed thereto a gear 35 6 which is in mesh with and drives a gear 7, the gear 7 having integrally connected therewith a pinion 7', the gear and pinion being connected with a shaft 8 journaled in a frame or bracket 9 which is loosely mounted 40 upon the motor shaft 5 and has one end thereof pivotally connected to the core of a solenoid 10 by a link 11. The solenoid and motor are in circuit with a battery 12 through wires 13, 14, 15 and 16, a switch 17 45 being provided to control the circuit. The operation is as follows:

When the switch 17 is closed the energization of the solenoid tilts the frame 9 to the position shown in Fig. 1 so as to throw the 50 pinion 7' in mesh with the gear 3, this operation taking place before or simultaneously with the starting of the motor 4. The gears rotate in the direction indicated by the arrows in Fig. 1 so that when the pinion 7' 55 is driving the gear 3, the effect is to main-

tain the pinion and gear in mesh, a stop 18 being provided to limit the swinging movement of the bracket; this stop being connected with any suitable part of the mechanism, such as the housing of the motor 4. 60 So soon as the engine starts and the circuit is broken the gear 3 becomes the driving element and the tendency is then to throw the pinion out of mesh therewith by swinging the end of the bracket upwardly to the position shown in dotted lines in Fig. 1, this action being assisted by a spring 19 connected to the pinion end of the bracket and also to some suitable stationary point 20.

While in the present case the gear 3 is 70 shown as forming a part of the fly wheel, yet in some installations this gear would be connected to the forward end of the crank shaft or to some other convenient point where it could have a driving connection to 75 the crank shaft.

Having thus described my invention, I claim:

1. In an apparatus of the character described, the combination, with the crank 80 shaft of an internal combustion engine, of a gear operatively connected therewith, an electric motor, a gear arranged to be driven thereby, a pinion arranged to tilt about the axis of said motor gear and in operative relation therewith, together with means for throwing said pinion in mesh with said engine gear, a stop for said pinion, the direction of rotation of said pinion being such as to tend to hold it in mesh with said engine 85 gear and against said stop.

2. In an apparatus of the character described, the combination, with the crank shaft of an internal combustion engine, of a gear operatively connected therewith, an electric motor and its shaft, a gear on said shaft revolvably connected therewith, a support pivoted on said shaft, a pinion supported in said support having an operative connection with said motor gear, means for tilting said 95 support to throw said pinion in mesh with said engine gear, a stop for said support, the direction of rotation of said pinion being such as to tend to cause it to travel about said engine gear until arrested by said stop. 100

3. In an apparatus of the character described, the combination with a crank shaft of an internal combustion engine, of a gear operatively connected therewith, an electric motor and its shaft, and a pinion tiltable 110

about the axis of said shaft and operatively connected therewith together with means for tilting the same in mesh with said gear, the parts being so disposed with respect to each other that when said pinion is in mesh with said gear, the axes of said pinion and the said shafts will be in substantial alinement with each other so that when said pinion is the driving element the tendency is to maintain it in mesh with said gear by the

driving action thereof and when said gear is the driving element the tendency is to throw said pinion out of mesh therewith by the driving action of said gear.

In testimony whereof, I have hereunto set my hand this 10th day of February, 1916.

JOHN O. HEINZE.
